UNITED STATES PATENT OFFICE.

JAMES BUSHEE, OF ATTLEBOROUGH, MASSACHUSETTS.

DESIGN FOR AN ORNAMENTAL CHAIN-LINK.

SPECIFICATION forming part of Design No. 14,045, dated July 10, 1883.

Application filed March 30, 1883. Term of patent 7 years.

To all whom it may concern:

Be it known that I, JAMES BUSHEE, a citizen of the United States, residing at Attleborough, in the county of Bristol, State of Massachusetts, have invented and produced a new and original Design for Ornamental Chain-Links, of which the following is a specification.

This invention relates to designs for ornamental chain-links; and my design consists of 10 the novel form of chain-link hereinafter described and claimed, and illustrated in the accompanying drawings, in which—

Figure 1 is a side view of an ornamental chain-link illustrating my design; Fig. 2, an 15 end or edge view of the same; Fig. 3, a plan or top view; and Figs. 4, 5, 6, and 7 illustrate modifications.

The design consists of a rectangular box, A, having its opposite sides provided with parallel transverse slots *o*, and having at its upper and lower ends rings *B*, which are arranged in the same plane, and an ornamental ring, *C*, encircling the rectangular box and passing through both the end rings, *B*, said 25 intermediate ring, *C*, being arranged at right angles, or substantially so, to the slots in the rectangular box. The box *A*, exhibiting slots

at its opposite sides, and the intermediate ring, *C*, encircling the box and passing through the end rings, present a chain-link of novel and 30 pleasing appearance. The intermediate ring, *C*, may be in the form of a plane-faced band, as in Figs. 1 and 2, or a band with an inverted-V-shaped periphery, as in Fig. 4, or a band ornamented by engraving, as in Fig. 5, or a 35 band with a periphery of rounded form, as in Figs. 6 and 7.

What I claim is—

The within design for a chain-link, composed of the rectangular box *A*, having its opposite 40 sides provided with transverse parallel slots *o*, the rings *B* at opposite ends of the box, and the ornamental ring *C*, encircling the box at right angles to the slots therein and passing through the end rings, as shown. 45

In testimony whereof I have hereunto set my hand and seal in the presence of two subscribing witnesses.

JAMES BUSHEE. [L. S.]
mark.
